UNITED STATES PATENT OFFICE.

ALONZO EGGLESTON, OF ROCHESTER, ILLINOIS.

BUTCHER'S REFRIGERATOR DISPLAY CASE.

Application filed June 1, 1925. Serial No. 34,115.

To all whom it may concern:

Be it known that I, ALONZO EGGLESTON, a citizen of the United States, residing at Rochester, in the county of Sangamon and State of Illinois, have invented a new Butcher's Refrigerator Display Case, of which the following is a specification.

This invention relates to a type of refrigerator display cases adapted to be used in butcher shops and places of the like for keeping meats and other foods cold while on display.

One of the purposes of this invention is to provide a refrigerator meat display case to be economically manufactured and secure a maximum of efficiency in keeping meats cool while on display in stores, butcher shops and the like and accomplish this result in the most economical manner.

A further object of my invention is to provide a butcher's refrigerator display case of the character hereinafter described that will protect the ice to a maximum extent, that will keep the water off the floor of the display compartments, that will enable the briny water melted from the ice to help in melting the ice steadily before such water leaves the ice container, to provide an ice container in a display case supported on rollers and other means adding to the conveniences of refilling the same; and to provide a refrigerator display case adapted to keep the air therein cold to the extent of an average daily temperature of from 5 to 15 degrees below freezing thus securing a maximum of benefit from the ice at a minimum cost for the ice.

A further object of my invention is to provide a display case of the character hereinafter described having a drain basin disposed in the floor thereof in which position the same is adapted to receive the drainage from the drip pans of the ice compartments; which drain basin is provided with an air trap to keep out the warm air; and a refrigerator display case having walls and faces and tops provided with a plurality of layers of material which will aid in keeping the ice to a low temperature.

I attain the objects of my invention above mentioned in the structure described in the annexed specification, re-cited in the claim and illustrated in the accompanying drawings in which like reference numerals indi-

cate the same structural parts in the several figures.

Referring to the figures: Figure 1, is a perspective of the display case of my invention showing the top, front and end views.

Figure 2 is a perspective of the same showing the top, end and rear views and also showing one of the ice compartments open with the inner door thereof let down for the rolling support of the ice container when the same is removed from the compartment for refilling.

Figure 3 is a front elevation of the refrigerator display case of my invention.

Figure 4 is a rear elevation showing all the rear doors closed and in addition showing how a convenient shelf is provided on each of the rear doors and made collapsible for the optional convenience of the butcher.

Figure 5 is a longitudinal section through the center of the refrigerator.

Figure 6 is a cross section of the refrigerator ice compartment exposing to view the ice container in its normal position when in use.

Figure 7 is an end elevation of the refrigerator display case of my invention.

Figure 8 is an isometric of a horizontal section of the entire refrigerator display case taken in a position to expose clearly to view a centrally disposed drain basin in the floor thereof, the drip pans normally positioned under the ice container for the drain pipe connections carrying the drainage from the drip pans to the drain basin.

Figure 9 is an illustration showing the relative position in elevation of the drain basin, the drip pans and pipes connecting the same.

Figure 10 is the side elevation of the ice container shown mounted on a supporting frame with truck rollers and also showing how the rear door lets down to a horizontal position, in line with the bracket supported tracks normally supporting the ice container on rollers; which door is adapted to support the ice container when the same is removed for refilling.

Figure 11 is a perspective of drain basin substantially built into the floor of the refrigerator showing in vertical section a $\frac{1}{4}$ cut away exposing the construction of the basin in detail.

Figure 12 is a vertical half section of the

same drain basin shown in its relative position to the floor of the refrigerator.

Figure 13 is a perspective of the air trap adapted to be seated in an inverted position over the central drain tube of the drain basin where the side holes in the air trap provide an outlet for the water draining away while the top of the case is adapted to provide an air trap to prevent warm air from coming into the refrigerator through the drain. Fig. 14 is the truck for the ice container.

Fig. 15 is a detail of the wall structure.

Referring now to the several details of my invention which are designated by numerals and which numerals indicate the same structural parts in the several figures I shall attempt to point out the relation of the several parts to the whole structure.

20 In the drawing numerals —1— and —2— refer to the end compartments respectively, which are adapted to be used as ice compartments. Numeral —3— indicates the display compartment in which meats and other perishables are normally kept for display and protection. A pair of ice containers —4— and —4'— when filled with ice and within the ice compartments are seated in a truck —12— mounted on rollers —39— and 25 resting on tracks —11— adapted to normally support the ice containers.

For instance, when it is desired to refill the ice containers —4— and —4'— the butcher opens the rear outer door —6— and 30 —6'— of the ice compartment and then opens rear inner door —5— and —5'— of the ice compartment by pulling on handle —13—. This door is pivoted along the bottom edge and is opened down to a horizontal position where it may be supported on handle —13—. A rubber sleeve —38— is provided in handle —13— which is adapted to prevent this handle from slipping on the floor when this door is let down to a 35 horizontal position supported thereon.

Truck —12— on its rollers —39— normally rests on track —11— in the ice compartments where this truck supports the ice container —4— and —4'— in the respective ice compartments and when inner door —5— and —5'— is resting in a horizontal open position it is adapted to provide a track support for the convenient removal of the ice container —4— and —4'— when 50 the container is pulled out of the ice compartment and refilled. It will therefore be seen that when the ice container is being refilled the inner door —5— and —5'— thus provides a table or shelf for the ice container's support and is found to be especially convenient and sanitary since it has turned up edges —19— or flanges integral with the door which are adapted to drain any water dripping from the ice container, back into the ice compartment drip pans.

Attention is called to the fact that ice containers are provided with a drain tube —14— and —14— which are securely attached to the bottom of the ice container over in a corner where they will not be in 70 the way and there adapted to normally drain the ice container after holding the briny water therein from the melted ice to a suitable level for the best melting effect on the ice before the briny water is permitted 75 to drain off at top of the tube.

Access to the display compartment is convenient through either of the rear doors —7—, —8—, —9— or —10—. A drain basin —20— is adapted to be built into the floor 80 —37— of the refrigerator. A pair of drip pans —15— and —16— are adapted to receive the dripping water from the ice containers respectively and from the drip pans the drainage is carried through drain tubes 85 —17— and —18— respectively to the drain basin —20—.

Drain basin —20— has an integral central tubular drain pipe projecting upward and downward from the floor of the drain basin. The downward projection is threaded for further drainage connection for carrying away the drainage while the upward projection terminates at a level approximately half way between the floor of the drain basin and the upper edge of the periphery of the main drain basin. An air trap —22— comprising an inverted cup, having a plurality of apertures —40— and adapted to be normally set down over central drain tube —21— in the drain basin, in which position air trap —22— is adapted to prevent warm air from coming into the refrigerator through the drain tube and also 100 shut out odors, coming from the drain tube carrying away the drainage while at the same time the openings in the air trap being positioned in elevation, normally about half way between the top of the central drain tube and the floor of the drain basin are adapted to pass the draining water at a level that permits sediment to settle in the floor of the basin and not pass out through the holes in the air trap and cause 105 the same to become stopped up.

The ice containers —4— and —4'— are provided with protective apertures in the sides for aiding in circulating the cold air from the ice. The display compartment is provided with horizontally disposed shelves —25— and —26— for the support of meat trays.

The end walls —27— and —28— of the respective ice compartments, the floor walls —29— and —30— and the top walls —31— and —32— respectively of the ice compartments are constructed of insulating materials of such substantial and insulating qualities as will insure the maximum of protection for the ice. The rear doors —6—

and —6'— are likewise built of a similar combination of substantial insulating materials, and each also has a collapsible shelf —41— and —41'— for the convenience of the butcher.

For instance: These doors and the walls for the ice compartment and the rear doors of the display compartment and the bottom of the refrigerator have an inner and outer 10 wood panel and having between these panels a heavy layer of cork and a sheet of moisture proof composition paper, another substantial layer of cork and a second sheet of water proof composition paper.

15 Referring to the display compartment, attention is called to the fact that the transparent walls on the top and in the front designated by numerals —33—34—35 and 36— are constructed of four layers of plate 20 glass, each layer spaced from the other to provide a suitable air space between, and adapted to provide a maximum of protection against allowing the air within the refrigerator from becoming heated by conduction 25 from the warm air outside which in ordinary refrigerators with only one thickness of glass can not be accomplished to a satisfactory extent.

It will be seen in the above description 30 that every effort is made to prolong the frozen state of the ice by keeping the temperature down in a most practical way, and it has been found, as a result of numerous tests made with this refrigerator that it 35 effectively keeps the air therein comparatively dry, and maintains the temperature

to a remarkably low level it being for instance a very common experience using this refrigerator when keeping a normal quantity of ice in the ice containers, to maintain 40 a temperature inside on warm summer days from day to day, to an average of between —15— and —25— degrees Fahrenheit.

To those skilled in the art it may be evident that minor changes may be made in some of the details of this device without departing from the spirit and scope of the invention; but in the above description I have explained the preferred embodiment of 45 my invention.

Having thus described the nature of my invention, what I claim is:

In a refrigerator having a display compartment and an ice compartment, an ice 55 container and support comprising a container on trucks, fixed tracks within the ice compartment for the trucks, an outer door and an inner door for the ice compartment; said inner door provided with 60 spaced rails aligned with said tracks and a U-shaped handle for said inner door, adapted to provide optional support therefor when the door is open; whereby the ice container may be optionally removed 65 from said ice compartment by rolling it out upon said rails of the opened inner door when it is desired to refill the ice container.

In witness whereof I hereunto set my hand and seal this 13th day of April A. D. 70 1925.

ALONZO EGGLESTON. [L. S.]
